FLARED HORN WAVE GUIDE ANTENNA

Lester C. Van Atta, Winchester, Mass., assignor,
by mesne assignments, to the United States of
America as represented by the Secretary of War

Application September 14, 1945, Serial No. 616,368

5 Claims. (Cl. 250—33.63)

1

This invention relates to antennas for communication systems and is particularly directed to an antenna having means for shaping the primary radiation pattern of a beam of electromagnetic energy emitted by a radiating element, such as a horn-type feed.

Such a radiating element has wide application. It can be used to match a wave guide transmission line to free space and thus may be used for radiating waves of electromagnetic energy directly to free space. However, its principal application is in feeding energy to, and illuminating, a reflector adapted to direct the radiant energy into free space in any desired beam pattern.

The gain, half power beam width and side lobes of the radiation pattern of an antenna having a paraboloidal reflector depend upon the phase and amplitude distribution of the radiation pattern of the reflector feed. The latter may be referred to as the primary pattern of the feed. For a circular dish-like reflector, the problem of feed is relatively simple. For a truncated paraboloidal reflector it is usually necessary to use a feed having a sharper beam in one plane than in the plane perpendicular to it.

One objective in designing a paraboloid antenna is to realize the maximum possible gain consistent with side lobe requirements. In order to get the highest gain, it is required to have a relatively uniform illumination across the aperture of the paraboloid and low spill-over at the edge. To achieve this, one can either shape the primary beam of a feed to fit a given reflector, or shape the reflector such as to form a truncated paraboloid to fit a given feed, or both.

The gain of a paraboloid antenna with a given feed is a maximum if the amplitude at the edge is half the average amplitude of the illumination over the aperture of the paraboloid. For a given feed, this provides a simple criterion for determining the size of the paraboloid. In general, the gain factor does not drop sharply with the increase of the aperture of the dish. Thus, a slightly bigger aperture can always be used to reduce the side lobes of the radiation pattern of the antenna. In most cases, however, the converse problem is encountered; namely, for a given paraboloid, how to shape the primary pattern of a feed to achieve the best results.

While an ordinary rectangular flared horn is the simplest type of feed to use for a truncated paraboloid, it is in some respects not entirely satisfactory from the standpoint of size as an increase in aperture means a fourfold increase in

length which makes the horn difficult to support. Furthermore, because of spilling over the edge of the dish and severely tapered illumination, the gain of a paraboloid antenna is usually low. In order to design an antenna of a high gain factor, it is necessary to shape a primary pattern of some special type to provide more uniform illumination with little energy shooting outside the reflector.

10 The principal object of the invention is to provide a horn type radiating element with means for controlling the primary pattern of the radiating element.

15 Another object of the invention is to provide a radiating feed element for an antenna having means adapted to furnish an approximation to uniform intensity across the aperture of the element for feeding a cut or truncated paraboloid. This may be accomplished according to this invention by controlling the phasing of the first and third harmonic amplitudes of the radiated energy by careful design of the dimensions of a box type horn so that the phase and relative amplitude of the first and third modes can be combined to form the desired result.

20 It is still another object of the invention to provide a novel horn-like radiating element adapted to produce a primary pattern of correct half power width and beam shape and which is more compact, smaller and lighter in construction than elements heretofore known.

25 Other objects, advantages and novel features of the invention will become apparent from the following description with reference to the accompanying drawing which is a perspective view of a box horn type radiating element according to one embodiment of the invention.

30 In the drawing, 10 designates the box horn radiating element according to this invention comprising a hollow pipe wave guide 11, a flared portion 12 and a box-like structure 13. Wave guide 11 is of rectangular cross-section, having parallel walls of wider dimension W_g , and is adapted to transmit energy of suitable modes and frequencies of operation from a source (not shown). Preferably the width W_g is made sufficient to support only the $TE_{1,0}$ mode of energy.

35 Flared portion 12 comprises upper and lower walls 14 and 15 and side walls 16, each having one end joined to the respective walls of wave guide 11 at throat 18. The opposite ends of the walls define rectangular mouth 19. Flared portion 12 may be flared in either or both of the H and E-planes (parallel to the directions of the H and E-vectors respectively). For example,

flared portion 12 is shown in the drawing as preferably being flared in the H-plane only, that is the upper and lower walls 14 and 15 are disposed at preferably equal angles of ϕ with respect to the respective walls of wave guide 11. Thus flared portion 12 has a wider dimension W_h at mouth 19 than at throat 18. Similarly, flared portion 12 may be flared in the E-plane wherein the dimensions between the side walls 16 are larger at mouth 19 than at throat 18.

Structure 13 is a rectangular box-like structure having one end open defining aperture 20, the wide dimension W_b of which is larger than the width of mouth 19 of flared portion 12. Preferably the narrow dimension n is equal to the corresponding dimension of flared portion 12 along the length of structure 13. However, if desired, the narrow dimension may also be flared outwardly away from flared portion 12 for at least a portion of the length of structure 13 to assist in correcting the impedance mismatch at aperture 20. The wall of structure 13 opposite to aperture 20 and which may be termed the rear wall 21 is provided with an opening disposed substantially centrally of the width of the wall and equal to the dimensions of mouth 19. Flared portion 12 is joined along the edges defining mouth 19 to the edges of the opening in the rear wall 21. Thus, flared portion 12 opens into structure 13 permitting energy to be transmitted from wave guide 11 through flared portion 12 and box-like structure 13 and radiated from aperture 20.

The width W_b of aperture 20 is sufficiently larger than width W_h so as to permit the existence in structure 13 of both the $TE_{1,0}$ and $TE_{3,0}$ modes of the energy propagated in wave guide 11. Even modes are eliminated by the symmetrical design and arrangement of the three parts of box horn 10.

The wave front of energy across mouth 19 will be substantially circular as indicated by the broken line P, due to the flaring of portion 12. The length L_h and the flare angle ϕ of flared portion 12 are chosen so that the phase variation D across W_h is preferably as small as possible,

$$D = \frac{W_h}{8L_h}$$

and if it is assumed, for example, that the energy across W_h be out of phase by

$$\frac{\lambda}{8}$$

λ being the wavelength at the desired frequency of operation, then

$$L_h = \frac{W_h^2}{\lambda}$$

From the geometry of the figure and calculation ϕ is determined by

$$\phi = \frac{W_h - W_s}{2L_h}$$

in radians.

The ratio of amplitudes of the two modes, that is of the first and third modes depends on the ratio of the width W_h of horn aperture 19 to the width W_b of structure 13. The smaller horns or flared portions 12 excite larger amplitudes of $TE_{3,0}$.

The amplitude of illumination across the rear of structure 13, that is, across mouth 19, is assumed to be $\cos(\pi x/W_h)$ for $0 < x < W_h/2$ and 0 for $W_h/2 < x < W_b/2$ where x is the lateral distance from the center line of box-horn 10. With con-

stant phase, the ratio of the third harmonic amplitude to the fundamental amplitude is given by

$$A_3/A_1 = \frac{\left[1 - \left(\frac{W_h}{W_b}\right)^2\right] \cos \left[\frac{3\pi W_h}{2W_b}\right]}{\left[1 - 9\left(\frac{W_h}{W_b}\right)^2\right] \cos \left[\frac{\pi W_h}{2W_b}\right]}$$

and these amplitudes are in phase at the rear of structure 13. Slight variations of the phase across W_h are not found to affect the results appreciably.

Now let W_b be restricted to the range $3/2 < W_b/\lambda < 5/2$, so that only the first and third modes are propagated to the aperture 20 of the box without rapid attenuation. The two modes have different wavelengths in the box so that their relative phase at aperture 20 depends upon the length L_b of structure 13. If λ_1 = first mode box wavelength, and λ_3 = third mode box wavelength, then, after traveling a length L_b , the phase difference $\beta = (2\pi L_b/\lambda_1) - (2\pi L_b/\lambda_3)$. When $\beta = \pi$, the third mode detracts directly from the fundamental in the center of the aperture and adds at the sides. Such modification has the effect of sharpening the main lobe in the Fraunhofer diffraction pattern of the box horn 10 and raising the side lobes. For a given box width W_b , the box length L_b is calculated from the following expression:

$$L_b = \left[4 - \left(\frac{\lambda}{W_b}\right)^2\right]^{\frac{1}{2}} - \left[4 - \left(\frac{3\lambda}{W_b}\right)^2\right]^{\frac{1}{2}} \text{ for } \beta = \pi$$

Calculation of the relative amplitude $F(\theta)$ radiated at an angle θ from the horn axis A is made under the following assumptions. (a) Each portion of the aperture field radiates in a $\cos^2(\theta/2)$ distribution, arising from the directional derivative of the field. (b) There is no radiation other than from the aperture field. (c) There are no multiple reflections within the box which contribute to the aperture field.

Thus, for constant total power and given aperture dimensions,

$$F(\theta) \sim \cos^2(\theta/2) (1 + A^2)^{1/2} \cdot \cos(\pi k/2) [(1/1 - k^2) + (3A/9 - k^2)]$$

where

$$k = (2W_b/\lambda) \sin \theta, \text{ and } A = A_3/A_1$$

The reflection coefficient of aperture 20 may, if desired, be adjusted by providing outstanding flanges along the wide edges of aperture 20 and preferably perpendicular to the wide walls of structure 13 (in the E-plane). Thus E-plane flanges may extend outwardly preferably for a distance of the order of a quarter wavelength.

For a given H-plane width of the radiation pattern, a flared box horn as described in accordance with this invention is considerably smaller in length and aperture than a usual type radiating horn. The following table illustrates the size advantage of a box horn according to this invention over ordinary radiating horns:

For a primary beam pattern with a full width of 60° between one tenth power points:

	Ordinary horn	Box horn
Approx. Aperture	2.0λ	1.5λ
Approx. Overall length	2.5λ	0.6λ
Side lobes db	26	14

It will be understood that the box horn 10 as described is adapted to produce the desired radiation pattern for illuminating a cut parabolic re-

flector and includes the desired advantages of more uniform intensity of the pattern, higher gain, smaller dimensions and more compact and lighter construction than horn type radiating elements heretofore used.

While there has been described what is at present considered the preferred embodiment of the invention, it will be obvious to those skilled in the art that various changes and modifications may be made therein without departing from the invention.

What is claimed is:

1. An antenna radiating element for radiating electromagnetic energy of a predetermined frequency, said element comprising a rectangular first wave guide having a uniform given width and a uniform given depth, the width and depth of said first wave guide being sufficient for said wave guide to support the $TE_{1,0}$ mode of said energy, but insufficient for said first wave guide to support higher modes thereof; a second wave guide having a rectangular cross-section, the width and depth respectively of said second wave guide at one end thereof being equal to said given width and depth respectively, the width of said second wave guide at the other end thereof being greater than said given width and the depth of said second wave guide at said other end thereof being at least as great as said given depth, whereby said second wave guide forms a flared horn having its throat at said one end thereof and its mouth at said other end thereof; a third wave guide having a rectangular cross-section, the width of said third wave guide at one end thereof being greater than the width of said mouth of said second wave guide and the depth of said third wave guide at said one end thereof, being at least as great as said given depth, the width and depth of said third wave guide at the other end thereof being at least as great as at said one end thereof, said third wave guide having an end member across said one end thereof, said end member having an opening therein, the width and depth respectively of said opening being equal to the width and depth respectively of said mouth of said second wave guide; one end of said first wave guide being connected to said second wave guide at the throat thereof, said second wave guide being connected to said third wave guide with said mouth in coincidence with said opening.

2. A radiating element as claimed in claim 1, wherein said opening is disposed centrally within said end member.

3. A radiating element as claimed in claim 1, wherein the width of said one end of said third wave guide is sufficient to support the $TE_{3,0}$ mode of said energy, but insufficient to support higher modes.

4. A radiation element as claimed in claim 1, wherein the width of said one end of said third wave guide is sufficient to support the $TE_{3,0}$ mode of said energy, but insufficient to support higher modes thereof, and the ratio of the width of said one end of said third wave guide to the width of said mouth is substantially equal to the value that satisfies the equation:

$$15 \quad (A_3/A_1) = \frac{\left[1 - \left(\frac{W_h}{W_b}\right)^2\right] \cos \left[\frac{3\pi}{2} \left(\frac{W_h}{W_b}\right)\right]}{\left[1 - 9 \left(\frac{W_h}{W_b}\right)^2\right] \cos \left[\frac{\pi}{2} \left(\frac{W_h}{W_b}\right)\right]}$$

20 where (A_3/A_1) is equal to a predetermined desired value of the ratio of the amplitude of the energy in the $TE_{3,0}$ mode to the amplitude of said $TE_{1,0}$ mode in said structure and where

$$25 \quad \left(\frac{W_h}{W_b}\right)$$

is the ratio of the width of said mouth to the width of said one end of said third wave guide.

5. An antenna radiating element as recited in claim 4 where the length L_b of said third wave guide is computed from the formula

$$30 \quad \frac{\lambda}{L_b} = \left[4 - \left(\frac{\lambda}{W_b}\right)^2\right]^{\frac{1}{2}} - \left[4 - \left(\frac{3\lambda}{W_b}\right)^2\right]^{\frac{1}{2}}$$

35 where λ is the wavelength of the desired frequency of operation and W_b is the width of said one end of said third wave guide, whereby the main lobe radiated is sharpened.
